[57] CLAIM

The ornamental design for a knife handle for slicing meat or similar article, substantially as shown and described.

DESCRIPTION

FIG. 1 is a side elevational view of a knife handle for slicing meat or similar article showing my new design, the broken line showing of a knife blade is for illustrative purposes only and forms no part of the claimed design;

FIG. 2 is a front elevational view thereof from the right of FIG. 1;

FIG. 3 is a rear elevational view thereof from the left of FIG. 1;

FIG. 4 is a top plan view thereof; and

FIG. 5 is a bottom plan view thereof.

The opposite side of FIG. 1 is a mirror image of the side shown in FIG. 1.
